No. 746,947.

PATENTED DEC. 15, 1903.

W. A. FRITZ.
CONCRETE MIXER.

APPLICATION FILED FEB. 27, 1903.

NO MODEL.

UNITED STATES PATENT OFFICE.

WILLIAM A. FRITZ, OF ZANESVILLE, OHIO.

CONCRETE-MIXER.

SPECIFICATION forming part of Letters Patent No. 746,947, dated December 15, 1903.

Application filed February 27, 1903. Serial No. 145,400. (No model.)

To all whom it may concern:

Be it known that I, WILLIAM A. FRITZ, a citizen of the United States, residing at Zanesville, in the county of Muskingum and State of Ohio, have invented a certain new and useful Improvement in Concrete-Mixers, of which the following is a specification.

This invention relates to the art of mixing concrete, mortar, and the like.

10 The essential object of the invention is to provide for mixing the material while in transit, and in particular while being elevated from the ground to the different floors of a building in course of erection.

15 It is furthermore designed to have the power for mixing the material transferred from the means for elevating the entire apparatus and in this manner to simultaneously carry out the elevating and mixing operations.

20 Another object is to provide for conveniently detaching the mixer proper from the elevating means in order that the latter may be employed independently of the former for hoisting stones, timbers, and other materials.

25 With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the present invention.

35 In the drawings, Figure 1 is a front elevation of a combined mixer and elevator constructed and arranged in accordance with the present invention. Fig. 2 is a side elevation 40 thereof. Fig. 3 is a detail enlarged sectional view taken through the upper portion of the apparatus. Fig. 4 is a detail cross-sectional view of the mixing-drum, and Fig. 5 is a fragmentary perspective view of the drum to show 45 some of the beaters thereof. Fig. 6 is a detail elevation showing the clutch connection between a sprocket-wheel and the drive-shaft.

Like characters of reference designate corresponding parts in each and every figure of 50 the drawings.

As hereinbefore indicated, the present apparatus is designed to carry out the mixing

operation while it is being elevated and lowered, as shown in the drawings.

The preferred embodiment of the invention 55 consists of a mixer proper in the form of a cylindrical receptacle or drum 1, which is provided with a door 2, hinged or slideable, whereby the material may be introduced and removed. As best indicated in Figs. 4 and 5, 60 it will be seen that a plurality of beaters 3 are secured to the interior of the drum, each beater being angular or substantially L-shaped and arranged in longitudinal series made up of spaced members, so that when the drum is ro- 65 tated these beaters will effectually break up and mix the material under treatment.

For the support of the mixing-drum there is a frame comprising an upper yoke-shaped member 4, which straddles or arches over the 70 drum and is provided at each end with downwardly-diverged leg-standards 5, (best shown in Fig. 2,) which are adapted to rest upon the ground or a floor, so as to support the apparatus when it is not being elevated. Just 75 above the mixing-drum the frame is provided with an intermediate cross-bar 6 to brace and stiffen the frame. The members of each pair of standards 5 are connected by a cross-bar 7, and each end of the mixing-drum is pro- 80 vided with an outwardly-directed spindle 8, which is journaled in the adjacent cross-bar 7 in order that the drum may be rotated upon its longitudinal axis. At the upper end of the frame there is a hanger consisting of op- 85 posite link members 9, the lower ends of which are bifurcated, so as to embrace the yoke 4, to which they are pivotally connected by means of suitable pivot-pins 10, whereby the links may be swung outwardly in opposite 90 directions, as indicated by dotted lines in Fig. 1 of the drawings, for a purpose as will be herein-after more fully described. The upper ends of the links are connected by means of a cross-bar 11, which is cylindrical 95 in shape and is mounted to rotate in suitable eyes or openings in the links. This cross-bar is removable and may be held against accidental endwise displacement by the pins or keys 12, inserted in suitable openings in the 100 bar; but it will of course be understood that one of these pins or keys may be dispensed with and a head substituted in lieu thereof. This change being obvious, it has not been

deemed necessary to illustrate the same in the drawings. The links are also detachably connected by means of an intermediate cross-bar 13, which has a pin or key 14 to removably hold it in place. An inverted substantially U-shaped bail 15 has its opposite ends provided with eyes for the rotatable reception of the cross-bar 11, and the upper end of this bail is provided with a swiveled link 17, with 5 which the cable 18 of a block and tackle is adapted to be connected. It will now be understood that the cross-bar 11 is also a shaft, and upon this shaft and between the opposite sides of the bail 15 are grooved pulleys 19, 10 which are fast upon the shaft, so as to rotate therewith. A pair of sprocket-wheels 20 are 15 also fast upon the shaft and disposed between the bail 15 and the respective links 9.

For elevating the apparatus a block and 20 tackle is employed, as best shown in Fig. 1 of the drawings, wherein it will be seen that the cable 18, connected to the hanger, passes upwardly and over one pulley member of a double block 21, which is hung in any preferred manner from a suitable support 22. Thence it passes downwardly and around one 25 of the pulleys 19, thence upwardly and over the other pulley member of the block 21, thence downwardly and around the other pulley 30 19, thence upwardly and over an elevated block 23, from which the cable portion 24 leads to a hoisting-drum or other suitable source of power. It will now be understood 35 that when the cable portion 24 is drawn in the direction of the arrow on Fig. 1 of the drawings the entire apparatus will be elevated, and, furthermore, as the device rises and the cable runs over the pulleys 19 the latter and the shaft 11 will be rotated during 40 the upward movement of the apparatus.

It is designed to transfer power from the shaft 11 to the drum 1 for rotating the latter, and this is carried out by means of a pair of endless sprocket-chains 25, which run over 45 the sprocket-wheels 20 on the shaft 11 and also over sprocket-wheels 26 on a shaft 27, mounted in suitable bearings 28 on the yoke portion 4 of the main frame and above the drum 1. The shaft 27 is projected at opposite 50 ends beyond the frame, and upon these projected ends are sprocket-wheels 29, over which run endless sprocket-chains 30, which also run over sprocket-wheels 31 upon the spindles 8 of the drum 1. By this arrangement 55 it will be understood that the shaft 11 is rotated by the elevating-cable, and the drum 1 is simultaneously rotated or driven from the shaft 11 by means of the gearing just described.

60 In using the apparatus it is first set upon the ground, as indicated in Figs. 1 and 2, and then the material is placed in the mixing-drum and the door 2 is closed and locked—as, for instance, by means of a turn-button 32.

65 Power is then applied to the cable to draw the same in the direction of the arrow in Fig. 1, whereby the entire apparatus is elevated

and the mixing-drum is simultaneously rotated, thereby effectually mixing the material during the elevation thereof.

In order that the apparatus may be capable of elevating material other than mortar, concrete, or the like—as, for instance, masonry and timbers—it has been designed to disconnect the main frame from the elevating means by removing the shaft 11 and the cross-bar 13 and also the pulleys 19 and the sprocket-wheels 20, the bail 15 being provided with a central pendent arm 33, having openings for the reception of the shaft 11 and the cross-bar 13 and provided at its lower end, with an enlarged hook or eye 34, with which a rope or cable may be engaged for elevating a stone or timber.

To facilitate the disengagement of the links 85 9 and sprocket-wheels 20 from the shaft 11 without withdrawing the latter from the bail 15, the upper end of each link is provided with a bearing-sleeve or perforate boss 35, projected at the inner side of the link and 90 rotatably receiving the shaft 11. This sleeve terminates short of the bail 15, and the adjacent sprocket-wheel 20 is provided at its outer side with a hollow hub 36, which rotatably embraces the sleeve 35 and is pierced by a 95 pin or key 37, which works in an external annular groove or way 38 in the sleeve, whereby the sprocket-wheel is capable of rotation upon this sleeve and is also connected therewith for removal from the shaft 11 when the 100 link 9 is swung outwardly. At the inner side of the sprocket-wheel there is a collar or 105 abutment 39, fast upon the shaft 11, and between the inner end of the hub of the sprocket and the abutment 39 is a clutch connection— 110 as, for instance, a projection fitting in a recess, as indicated at 40 in Fig. 6, whereby the sprocket is interlocked with the shaft for simultaneous rotation therewith and may be slid away from the abutment 39 and out of engagement therewith when the link 9 is swung outwardly.

It is desired to call attention to the fact that as the elevating-cable 18 passes in opposite directions around the pulleys 19 on the shaft 11 one of these pulleys should be loose upon the shaft and the other fast thereon—as, for instance, by means of a spline or key 41, (shown in Fig. 3 of the drawings,) whereby the fast pulley is designed to drive the 115 shaft and the loose pulley to rotate independently thereon.

Having thus described the invention, what is claimed, and desired to be secured by Letters Patent, is—

1. In a device of the character described, the combination with a frame having leg-standards, of a receptacle rotatably mounted thereon, elevating means including block and tackle connected to the frame, a pulley carried by the frame and engaged by the tackle for rotation thereby, a counter-shaft carried by the frame, and drive connections between the pulley and the counter-shaft and

also between the counter-shaft and the receptacle.

2. In a device of the character described, the combination with a frame, of a mixing-drum rotatably mounted thereon, and provided with a gear, a counter-shaft upon the frame, a drive connection between the counter-shaft and the gear, links rising from the frame, a shaft journaled in the links, a bail supporting the shaft, a pulley upon the shaft, a gear upon the shaft, a drive connection between the gear and the counter-shaft, and elevating means including block and tackle connected to the bail and engaging the pulley to rotate the same and the shaft.

3. In a device of the character described, the combination with a yoke-shaped frame, of a mixing-receptacle mounted upon the frame and provided with spindles, gears upon the spindles, a counter-shaft mounted upon the frame and above the mixer, drive connections between the counter-shaft and the gears, links rising from the top of the frame, a shaft rotatably supported upon the links, a gear and a pulley mounted upon the shaft, a drive connection between the said gear and the counter-shaft, a bail rotatably supporting the shaft, and elevating means including block and tackle connected to the bail and

also engaging the pulley to rotate the latter 30 and its shaft.

4. In a device of the character described, the combination with a frame, of a mixing-receptacle rotatably mounted thereon, a drive-shaft carried by the frame, a drive connection between the shaft and the receptacle to rotate the latter, and a hoisting device embodying a block and tackle, the cable of which runs in opposite directions around fast and loose pulleys upon the shaft.

5. In a device of the character described, the combination with a frame, of a mixing-receptacle rotatably mounted thereon, links pivoted to the frame and rising therefrom and provided at their upper ends with laterally-directed bearing-sleeves having external annular grooves, sprocket-wheels rotatably mounted upon the sleeves and provided with projections working in the grooves, clutch connections between the sprocket-wheels and 45 the drive-shaft, a pulley fast upon the shaft, and a hoisting device including a cable running over the pulley.

WILLIAM A. FRITZ.

In presence of—

A. L. PHELPS,
W. L. MORROW.
